UNITED STATES PATENT OFFICE.

JAMES McCABE, OF MINNEAPOLIS, MINNESOTA.

LOADING APPARATUS.

No. 891,183.

Specification of Letters Patent. Patented June 16, 1908.

Application filed January 25, 1907. Serial No. 354,076.

To all whom it may concern:

Be it known that I, JAMES McCABE, citizen of the United States, residing at Minneapolis, in the county of Hennepin and State of Minnesota, have invented a new and useful Loading Apparatus, of which the following is a specification.

This invention relates to a loading apparatus of that type employing a forwardly extending gathering fork that is pivotally mounted on its vehicle so as to be actuated by means of the forward movement of the latter through suitable manually controlled mechanism arranged between the fork and one of the wheels of the vehicle, and it relates more particularly to a loading apparatus in which the fork is adapted to deposit its contents into a suitable box or receptacle carried by the vehicle at the rear of the fork.

The invention has for one of its objects to provide an apparatus for loading shocks of hay, grain, fodder, or other material, into the body of the vehicle in a simple, convenient and effective manner.

A further object of the invention is the provision of a pivotally mounted gathering fork which is actuated by means of a flexible element arranged to simultaneously wind at one end and unwind at the other end on oscillatory quadrant or sheave segments, one quadrant or sheave segment being actuated from one of the axles of the vehicle through a gearing that is adapted to be clutched and unclutched by the attendant.

Another object is the employment of a buffer arranged on the front end of the vehicle box or body in the path of the fork so as to cushion the latter at the end of its lifting stroke.

A further object is to improve and simplify the construction and operation of apparatus of the character referred to so as to be comparatively simple and inexpensive to manufacture and keep in repair, thoroughly reliable and efficient in use, and convenient to manipulate.

With these objects in view, and others, as will appear as the nature of the invention is better understood, the invention comprises the various novel features of construction and arrangement of parts, which will be more fully described hereinafter and set forth with particularity in the claims appended hereto.

In the accompanying drawing, which illustrates one of the embodiments of the inven-

tion, Figure 1 is a side elevation of the loading apparatus. Fig. 2 is an enlarged detail view of the winding member. Fig. 3 is a vertical section on line 3—3 of Fig. 2.

Corresponding parts in the several figures are indicated throughout by similar characters of reference.

Referring to the drawing, A designates the running gears of a four wheeled vehicle on which is pivotally mounted a tilting box or body B, and hingedly supported on the running gear at a point in front of the box is a gathering fork C. The running gear comprises front and rear supporting wheels 1 and 2 on which the frame 3 is carried. The tilting box is of that type having its axis of tilting slightly to the rear of its middle so that the forward portion of the box will rest normally on the frame 3 while the rear portion overhangs the latter, the axis of tilting being the axle 4 for the rear wheels. The fork C comprises a plurality of parallel tines 5 suitably connected together and pivoted at their rear ends on the shaft 6, the said shaft being journaled in bearings 7 (of which one is shown in the present illustration) and located slightly in advance of the front end of the box 3. Carried on the front of the box is a buffer D comprising a frame 8 pivoted at its bottom to the box B at the point 9. This frame is yieldingly held in a forwardly inclined position by means of the extension spring 10 located under the box with its rear end 11 anchored thereto and its front end connected to the frame 8. The buffer D is thus located in the path of the fork C as it moves on its lifting stroke, thereby cushioning the latter and bringing it gradually to rest without striking forcibly against the box B.

The mechanism for actuating the fork C is constructed as follows:—Adjacent the front of the frame 3 of the vehicle is a sheave segment or quadrant 12 fulcrumed at 13 on the frame 3 at a point slightly in front of the box B. This sheave segment or quadrant is composed of a curved member 14 of V-shaped cross section, and radial arms 15 to which the said member is connected. One of the arms 15 is disposed normally in a horizontal position and is provided with an extension 16 that is flexibly connected by links 17 to the fork C adjacent its middle. Coöperating with the sheave segment or quadrant 12 is a second sheave segment or quadrant, designated generally by 18 and more clearly shown in Figs. 2

and 3. This sheave segment or quadrant is composed of a curved metal strip 19 of V-shaped cross section and connected to the outer end of the right angularly disposed 5 arm 20. The said arms and groove member 19 are provided with a plurality of apertures 21 whereby the parts can be adjustably connected in different positions by bolts 22 passing through registering apertures. The 10 inner ends of the arms 20 are held in sockets 23 formed on a disk or wheel 24, rivets or other fastenings 25 being employed to hold the parts together. Associated with these sheave segments or quadrants 12 and 18 is a flexible 15 element 26, such as a wire cable, that has both ends fixed to the bottom portions of the members 14 and 19 of the sheave segments or quadrants, the arrangement being such that the cable will wind up in the groove of 20 one of said members while unwinding from the groove of the other member. Of this motion transmitting mechanism the sheave segment or quadrant 18 is the driver, and the same is adapted to produce a draft on the cable 26 so that the sheave segment or quadrant 12 is rocked and the fork C raised to its unloading position. The unloading position of the fork is such that the latter will return to its initial position by its own weight, 25 when the power is released from the actuating sheave segment or quadrant 18. The cam 18 is mounted on the rear axle 4 and is adapted to be clutched thereto when the operator desires to raise the fork. The clutching and unclutching of the sheave segment or quadrant with the axle is accomplished by means of a gear constructed on the compensating type and comprising a wheel 27 keyed 30 to the rear axle 4 and carrying a plurality of pinions 29 that mesh with the teeth on the wheels 24 and 30, which latter are loosely mounted on the axle. To cause the sheave segment or quadrant 18 to be actuated, it is merely necessary to arrest the movement of 35 the wheel 30. This causes the pinions 29 to actuate the wheel 24 forming part of the cam structure 18. To arrest the movement of the wheel 30, the latter is provided with a plurality of radially extending projections 40 31, and mounted on the frame 3 adjacent the wheel is a lever or stop 32 fulcrumed at 33 and carrying a roller 34 that is adapted to engage the periphery of the wheel 30 and abut any one of the projections 31. This 45 stop device 32 is connected by the rod 35 to the operating lever 36 fulcrumed adjacent the front of the frame 3.

From the foregoing description, taken in connection with the accompanying drawing, 60 the advantages of the construction and of the method of operation will be readily apparent to those skilled in the art to which the invention appertains.

In operation, the vehicle is driven forwardly by horses, or any other suitable

means, the draft device for attaching the horses to the vehicle being eliminated in the present instance, since the same does not enter into the present invention.

Assuming that the fork C has received its 70 load, and the attendant has thrown the lever 36 forwardly, the fork is raised in the following manner. The stop 32 is moved from its dotted line position, Fig. 2, to its full line position through the movement of the operating lever 36. The wheel 30, which normally rotates with the axle 4 by meshing with the pinions 29, is immediately brought to rest so that the wheel 24 of the sheave segment or quadrant 18, which has in the meantime been idle, is actuated by the pinions 29 which revolve with the wheel 28. The sheave segment or quadrant 18 is thus turned so as to cause the cable 26 to wind thereon and unwind from the sheave segment or 85 quadrant 21. Since the said cable is connected with the fork C, the latter is raised so as to deposit its load into the box B. Near the end of the unloading stroke, the fork strikes against the buffer D so as to permit 90 the stroke to end gradually. As soon as the material on the fork is deposited, the operator releases the lever 36 so that the fork can return to its normal position. As the fork swings down, the cable 26 winds up on the 95 sheave segment or quadrant 12 and upwinds from the sheave segment or quadrant 18. By releasing the lever 36, the wheel 30 is free to turn during the return stroke of the sheave segment or quadrant 18. 100

What is claimed is—

1. In an apparatus of the class described, the combination of a vehicle, a box mounted thereon, a loading fork carried by the vehicle, and a cushioning device arranged to 105 cushion the fork tines at the end of their unloading stroke.

2. In an apparatus of the class described, the combination of a vehicle, a tiltable receptacle mounted thereon, a loading fork carried by the vehicle, and a cushioning device mounted on the receptacle in the path of the fork tines to cushion the latter at the 110 end of their unloading stroke.

3. In an apparatus of the class described, the combination of a vehicle, a receptacle mounted thereon, a swinging fork carried by the vehicle, a frame hingedly mounted on the receptacle in the path of the fork, and a spring on the receptacle for yieldingly holding the 115 said frame.

4. In an apparatus of the class described, the combination of a vehicle, a receptacle mounted thereon, a loading fork on the vehicle, separate winding devices one on a 120 stationary part of the vehicle and the other on an axle of the latter, a connection between the first of said devices and the fork, a flexible element connected with the devices to wind on one while unwinding from the other, 125

and means for actuating the device on the axle by clutching the same to the latter.

5. In an apparatus of the class described, the combination of a vehicle including a rotating axle, a loading fork on the vehicle, a sheave segment or quadrant fulcrumed on the vehicle, a second sheave segment or quadrant loosely mounted on the axle, the center of said quadrant being eccentric to said axle, 10 a flexible element connected with the sheave segments or quadrants to wind on one while unwinding from the other, a flexible connection between the first mentioned sheave segment or quadrant and the fork, and a device 15 for clutching the second sheave segment or quadrant to the axle.

6. In an apparatus of the class described, the combination of a vehicle including a rotating axle, a loading fork on the vehicle, an 20 oscillating structure on the vehicle connected with the fork to actuate the same, means for oscillating the structure, and a differential gear whereby the said means are actuated by said axle.

25 7. In an apparatus of the class described, the combination of a vehicle including a rotating element, a swinging fork mounted on the vehicle, and a mechanism for elevating the fork, said mechanism comprising a winding device loosely mounted on the element, and a differential gear adapted to connect the winding device to the rotating element.

8. In an apparatus of the class described, the combination of a vehicle including an 35 element rotated by the movement of the vehicle, a fork mounted on the vehicle, a winding device loosely mounted on the element, means connected with the device and fork for actuating the latter, a differential gearing 40 on the element for connecting the latter with the device, and a manually controlled means for rendering the gearing operative or inoperative.

9. In an apparatus of the class described, 45 the combination of a vehicle including an axle, a loading fork on the vehicle, and a mechanism for actuating the fork by the axle, said mechanism comprising a winding device loosely mounted on the axle and carrying teeth, a member keyed to the axle, a gear wheel loosely mounted on the axle, a pinion on the member meshing with the gear wheel and teeth on the winding device, and means for controlling the said gear wheel to 55 cause the winding device to move with the axle.

10. In an apparatus of the class described, the combination of a vehicle including an axle, a loading fork on the vehicle and a 60 mechanism for actuating the fork by the axle, said mechanism comprising a winding device having an oscillating movement and mounted on the axle, a member loosely mounted on the axle, a device rotating with 65 the axle and arranged to be clutched with

the winding device, and means operating on the said member for clutching the said devices together.

11. In an apparatus of the class described, the combination of a vehicle, a loading fork 70 on the same, and a mechanism for actuating the fork by the movement of the vehicle, said mechanism including a winding device comprising a cam-shaped grooved member, and a supporting structure to which the member is 75 adjustably attached.

12. In an apparatus of the class described, the combination of a vehicle, a loading fork on the same, and a mechanism for actuating the fork by the movement of the vehicle, said 80 mechanism comprising a flexible element, a curved grooved member in which the element winds, arms on which the member is adjustably mounted, a disk supporting the arms, and a clutch cooperating with the disk. 85

13. In a device of the kind described, the combination with a truck having traction wheels and a box or receptacle thereon, of a fork pivotally mounted in front of said box, a sheave segment connected to said fork, a 90 co-operating sheave segment having means for connecting it to and disconnecting it from one of the traction wheels of said truck, and a cable attached to the said two sheave segments at such points that the fork will be 95 raised with an accelerated movement and a maximum power is rendered available for overcoming the inertia of and imparting initial movement to the fork and its load.

14. In a device of the kind described, the 100 combination with a truck having traction wheels and a box or receptacle, of a fork pivoted to the truck frame in front of said box, a pair of sheave segments connected to said fork, a pair of sheave segments loose with 105 respect to the traction wheels of said truck, means for connecting said latter sheave segments to said traction wheels, at will, and means for disconnecting them at the proper times, and cables connecting the corresponding sheave segments and arranged to raise said fork with an accelerated movement and with a maximum initial power. 110

15. In a device of the kind described, the 115 combination with a truck having rear traction wheels, front steering wheels and a box, of a fork pivoted to the truck frame in front of said box, lifting levers pivoted to said frame and connected to said fork, adjustable sheave segments carried by said lifting levers, adjustable rear sheave segments mounted in the vicinity of the rear traction wheels, cables connecting the front and rear sheave segments, and means for connecting said rear sheave segments to and disconnecting the 120 same from said rear traction wheels. 125

16. In a device of the kind described, the combination with a truck having front steering wheels, a rear axle, traction wheels mounted on and arranged to drive said axle, 130

and a box on the truck frame, of a fork pivoted to the truck frame in front of said box, forward sheave segments connected to said fork at the sides thereof, bevel gears loose on 5 said rear axle, sheave segments carried by said bevel gears, cables connecting the corresponding front and rear sheave segments, driving hubs secured to said rear axle adjacent to said bevel gears and carrying pinions 10 meshing therewith, other bevel gears loose on said axle meshing with said pinions and provided with stop lugs or shoulders, and

means operative, at will, for engagement with the stop lugs or shoulders of said bevel gears, to lock the latter temporarily against rotation. 15

In testimony that I claim the foregoing as my own, have hereunto affixed my signature in the presence of two witnesses.

JAMES McCABE.
